Primary Examiner — Catherine Ho

(57) **CLAIM**

The ornamental design for the welcome sign set with interchangeable components, as shown and described.

DESCRIPTION

FIG. 1 is an exploded front perspective view of the welcome sign set with interchangeable components, showing our new design;

FIG. 2 is an exploded rear perspective view thereof;

FIG. 3 is an exploded front view thereof;

FIG. 4 is an exploded rear view thereof;

FIG. 5 is an exploded left side view thereof;

FIG. 6 is an exploded right side view thereof;

FIG. 7 is an exploded top view thereof;

FIG. 8 is an exploded bottom view thereof;

FIG. 9 is an exploded perspective view thereof shown in a first configuration of use;

FIG. 10 is an exploded perspective view thereof shown in a second configuration of use;

FIG. 11 is an exploded perspective view thereof shown in a third configuration of use;

FIG. 12 is an exploded perspective view thereof shown in a fourth configuration of use;

FIG. 13 is an exploded perspective view thereof shown in a fifth configuration of use;

FIG. 14 is an exploded perspective view thereof shown in a sixth configuration of use;

FIG. 15 is an exploded perspective view thereof shown in a seventh configuration of use;

FIG. 16 is an exploded perspective view thereof shown in an eighth configuration of use;

FIG. 17 is an exploded perspective view thereof shown in a ninth configuration of use;

FIG. 18 is an exploded perspective view thereof shown in a tenth configuration of use;

FIG. 19 is an exploded perspective view thereof shown in an eleventh configuration of use; and,

FIG. 20 is an exploded perspective view thereof shown in a twelfth configuration of use.

The broken lines in the drawings illustrate portions of the article and form no part of the claimed design.

1 Claim, 20 Drawing Sheets
